United States Patent Office.

ALLEN CALKINS AND WILLIAM TOWER, OF ALMONT, MICHIGAN.

Letters Patent No. 63,012, dated March 19, 1867.

IMPROVED MACHINE FOR FORMING EAVES TROUGHS.

The Schedule referred to in these Letters Patent and making part of the same.

TO ALL WHOM IT MAY CONCERN:

Be it known that we, ALLEN CALKINS and WILLIAM TOWER, of Almont, Lapeer county, and State of Michigan, have invented a new and useful Improvement in Machines for Forming Eave Troughs and Conductor Pipes; and we do hereby declare that the following is a full, clear, and exact description thereof, which will enable others skilled in the art to make and use the same, reference being had to the accompanying drawing, forming part of this specification, in which—

Figure 1 is a top or plan view of our improved machine.

Figure 2 is a vertical longitudinal section of the same, taken through the line $x\ x$; fig. 1.

Figure 3 is a vertical longitudinal section of the same, taken through the line $y\ y$, fig. 1.

Figure 4 is a vertical cross-section of the same, taken through the line $a\ z$, fig. 1.

Figure 5 is a vertical cross-section of the same, taken through the line $x\ x$, fig. 1.

Similar letters of reference indicate like parts.

Our invention has for its object to furnish an improved machine, by means of which the manufacture of eave troughs and conductor pipes may be greatly facilitated.

And it consists, first, in the combination of bars with each other and with the frame of the machine, for the purpose of bending over the edge of the metallic strips to receive the stiffening wire.

Second, in the combination of the bars with each other and with the frame of the machine for the purpose of partially forming the eave troughs.

Third, in the combination of the dies, sliding head-block, nippers, rope, shaft, gear-wheels, and shank with each other and with the frame of the machine.

And fourth, in the combination of the dies, guide-bar, nippers, rope, shaft, gear-wheels, and crank with each and with the frame of the machine.

A is the frame of the machine; B is a metallic bar, attached to the upper edge of the frame A of the machine. A narrow groove or channel is formed between the bar B and the edge of the frame A, to which it is attached, for the reception of the edge of the strip from which the trough or pipe is to be made, as shown in fig. 5. C is a bar hinged to the edge of the frame A, as shown in fig. 1. D is a bar attached to the side of the frame A. The upper side of the bar D is so shaped as to give the required form to the eave trough. E is a bar hinged to the top edge of the frame A, as shown in fig. 5. The side of the bar E that shuts down upon the bar D is so formed as to fit the said bar, giving form to the strip of metal from which the trough is to be made, by pressing it between the said bars D and E. F is a bar hinged to the bar E, and which by being shut down upon the bar D, gives form to the vertical side of the trough. G is a block having a slit cut through it of the exact form it is desired the trough should have, and by passing the trough through this slit or die it is brought to the proper form. H is the sliding head-block, which slides in a groove or channel formed upon the upper side of the frame or table A. The block H is made of such a form as to fit into the said trough, and it has shoulders h' , against which the end edges of the said trough press as it is drawn forward through the die G. I are the nippers by which the end of the trough is grasped to draw it through the die G. To these nippers is attached one end of the rope J, which passes around the pulley K, pivoted to the end of the table or frame A, as shown in figs. 1 and 2, and its other end is attached to the shaft L, as shown in fig. 2. The shaft L revolves in bearings in the frame A of the machine, and to its projecting end is attached the gear-wheel M, the teeth of which mesh into the teeth of the gear-wheel N, to which the crank O is attached. P is the die for bringing the conductor pipe into the required shape. The outer part p^1 of the die P has a circular hole formed through it. p^2 is a plug or former, which is supported within the hole through the part p^1 by a screw, p^3 , projecting from its rear side, which passes through a hole in the support R, upon which screw are placed nuts S^1 and S^2 , by means of which the said former p^2 is regulated. T is a guide attached to the lower side of the part p^1 of the die P, which enters a slot in the lower part of the former p^2 , and which guides the edges of the pipe into such a position that they will enter the channels between the plates u^1 and u^2 of the bar U, as shown in fig. 5. One end of the bar U is pivoted to the face of the former p^2 , as shown in fig. 3, and the other end rests against a block V, attached to the frame or table A of the machine. The bar U is square, and is placed with a corner downward, as shown in fig. 5, and to the sides adjacent to the lower corner are attached the plates u^1 and u^2 , in such a way that channels or grooves may be formed between the said plates u^1 and u^2 and the bar U, for the

reception of the edges of the pipe. The pipe is drawn through the die P and around the bar U by the nippers I, the rope J of which passes over the pulley W, and thence to the shaft L, as before described.

In making eave troughs with this machine the zinc or other material of which the troughs are to be made is cut into strips about seven feet long, and of the necessary breadth to form the trough. The edge of this strip is then placed in the channel beneath the bar B, and the bar C turned up into the position shown in fig. 5. This bends the edge of the strip over upon itself for the reception of the stiffening wire, which is then put in and the edge closed down upon it. The wired edge is then placed in the crease or channel between the bar D and the side of the frame or table A, and the bars E and F turned down. This partially forms the trough, which is then removed from the bars D E F, and its end passed through the slit in the die G, and upon the block H, with its end edges resting against the shoulders h' . The end of the trough is then grasped with the nippers I, and by turning the crank O it is drawn through the die G, which completes its formation. In making conductor pipes, the material of which the pipe is to be made is cut into strips about seven feet long and of the required breadth. The edges are then turned over by means of the bars B and C. It is then bent up and passed through the die P, the guide T guiding its turned-over edges into such a position that they will pass into the channels between the plates w^1 and w^2 and the bar U. The end of the pipe is then grasped by the nippers I, and the rope J passed over the pulley W. Then by turning the crank O the pipe is drawn through the pipe P, upon the bar U. The bar U is then turned over and the edges of the pipe soldered, after which it may be removed from the bar U.

We claim as new, and desire to secure by Letters Patent—

1. The combination of the bars B and C with each other, and with the frame A of the machine, substantially as described and for the purpose set forth.
2. The combination of the bars D E F with each other, and with the frame A of the machine, substantially as described and for the purpose set forth.
3. The combination of the die G, sliding-block H, nippers I, rope J, shaft L, gear-wheels M N, and crank O with each other, and with the frame A of the machine, substantially as described and for the purpose set forth.
4. The combination of the die P, guide T, bar U, nippers I, rope J, shaft L, gear-wheels M N, and crank O with each other, and with the frame A of the machine, substantially as described and for the purpose set forth.

ALLEN CALKINS,
WM. TOWER.
